UNITED STATES PATENT OFFICE.

ROBERT HOPE-JONES, OF NEW YORK, N. Y.

ORGAN.

No. 849,241.

Specification of Letters Patent.

Patented April 2, 1907.

Application filed April 22, 1904. Serial No. 204,374.

To all whom it may concern:

Be it known that I, ROBERT HOPE-JONES, a citizen of Great Britain, and a resident of New York, in the county of New York and State of New York, have invented certain new and useful Improvements in Organs, of which the following is a full, clear, and exact specification.

This invention relates to an improved economical and convenient method of controlling stops and couplers in pipe-organs. Its object is to provide means whereby in drawing on the stops or couplers in one department of the organ a stop or stops forming a suitable accompaniment thereto may also be drawn on in another department of the organ. The mechanism by which these results are obtained may be pneumatic, electric, or electropneumatic.

Although this invention may be used in connection with any two departments of the organ, it finds its most frequent use in connection with the pedal-department in providing a suitable bass for whatever stops are drawn upon any of the manual-departments, and it is therefore described herein in connection with the pedal-department of the organ, although it will be understood that its use is not limited thereto.

Figure 1 of the drawings is a front view of a portion of the console of a two-manual organ. Fig. 2 is a side view in section through the line 2 2 of Fig. 1 looking in the direction of the arrow. Fig. 3 is a fragmentary view of a portion of the console in section through the line 3 3 of Fig. 1. Fig. 4 is a diagrammatic view showing the arrangement and relation of the parts when connected and controlled by electric devices. In this view there is shown only a portion of the stop and coupler tablets of each department of the organ, and the tablets and suitable bass rods are shown at right angles to their true position relative to their connected parts in order to show in a single view the relation of the parts. Fig. 5 is a similar view showing one method of connecting and controlling the parts by pneumatic devices. Fig. 6 is a side view, and Fig. 7 a front view, of a pair of associated composition pedals.

In securing the automatic action of the pedal stops and couplers so that they may at will provide the desired suitable bass a set of small motors is provided for drawing all pedal stops or couplers into their off position, and a set of larger motors is provided

for moving the desired stops or couplers into their on position. A pneumatic or electro-pneumatic valve is provided for supplying wind under pressure simultaneously to all of the aforesigned off motors, and a set of independent pneumatic or electropneumatic valves is provided for supplying wind independently to each of the aforesigned on motors.

In arranging the suitable bass mechanism to operate in connection with the composition pedals affecting the stops and couplers of the manual-department of the organ subsidiary composition pedals are provided and connected by electric, pneumatic, or electropneumatic means with the stops and couplers of the pedal-department of the organ. These subsidiary composition pedals, or those parts of them which are engaged by the foot of the organist, are preferably placed below the ordinary composition pedals, so that after a certain amount of movement of the upper pedal the lower pedal will also be operated, although either of the pedals may be operated independently. Each subsidiary composition pedal is arranged to draw on such a stop or stops in the pedal-department as will form a suitable accompaniment to the combination of stops drawn on by the associated composition pedal above it.

Referring to the drawings, the console 11 has two rows of manual-keys 12 and 13, the upper one, 12, representing the swell-organ and the lower one, 13, the great organ. The console 11 is provided in its upper portion with a series of actions comprising stop keys or tablets which control the stops and couplers of the organ, the series beginning with 102 representing the tablets affecting the pedal-department, while those beginning with 126 and 123 represent those affecting the great and swell manual-departments, respectively. The outer ends of the tablets project through the casing of the console to within convenient reach of the organist. Each of the tablets, as 105, is provided with a contact-plate 111, Fig. 2, and a pair of contacts 112 and 113, so that the movement of the tablet on the pivot 106 will close the circuit through one or the other of the contacts 112 or 113, the former throwing off the connected stop or coupler and the latter bringing it on. A spring 109 tends to keep each tablet in either position after it has been operated.

Below each manual is a suitable bass push-button or knob 14 or 24, carried by a rod 15

or 25, which at its forward end is supported by and works in the key-slip 17, while its rear end passes through and works within a board 18. A similar rod placed alongside 5 one of the rods 15 or 25, preferably the former, carries on its outer end a throw-off button or knob 23, Fig. 1. The rods 15 or 25 and the rod of the throw-off knob 23 are connected by means of the pivoted latch-board 20 21 in a manner similar to that described in connection with Figs. 56 and 58 of my Patent 522,209, of July 3, 1894, so that only one of the knobs 14, 24, or 23 can rest in its pushed-in position at the same moment. The 25 pushing in of either of the knobs 14 or 24 will release the other knob, while the pushing in of the knob 23 operates to release and push out both of the knobs 14 and 24. In describing the construction of this suitable bass 30 mechanism the lower or great organ rod will be considered. The operation of the upper or swell organ rod is similar, except for such differences as will be hereafter noted. On the suitable bass rod 25, Fig. 2, are three insulated metallic collars 28, 29, and 30, (coated 35 on their front sides with cloth to prevent excessive noise in action,) which when the rod is in its "on" or pushed-in position close electric circuits through the three upper contacts 32, 33, and 34 and the lower contacts 36, these latter being connected to the battery-wire 48, while the wires from the three upper contacts are led off independently. The circuit closed by the collar 28 serves to 40 throw to the "off" position any of the pedal stops or couplers which may be on at the time the circuit is closed. The circuit of the collar 29 serves to couple the great keys to those of the pedal-organ. The circuit of the 45 collar 30 serves to throw on the suitable pedal-stops whenever the corresponding manual-stops are thrown on, as explained more fully hereinafter. The three insulated collars 28, 29, and 30 could obviously be 50 combined in one, with the contacts suitably arranged around its periphery. For the sake of clearness, however, they have been drawn separately. The circuit of the fourth collar 31 is for use when the swell-organ is coupled to the great organ, as will be more 55 fully explained hereinafter.

The wire 38 of the contact 32 is connected to the magnet 51 of an electro-pneumatic valve similar to those described in my Patent 522,209, of July 3, 1894. Below the holes of the magnet in the recess 54 is a valve-disk 52, which normally rests over the end of the hole 56 and keeps it closed by means of the wind-pressure from the chamber 63 through 60 the hole 55 between the poles of the magnet, the chamber 63 being connected with a wind-chest of the organ. The hole 56 leads to the chamber 64, which is open to the atmosphere. The valve-disk 52 is made of soft 65 iron, so as to form an armature for the mag-

net, and may be covered with kid or otherwise suitably prepared to make an air-tight closure. From the recess 54 a passage 61 leads to the interior of a bellows 62, provided with a lever 65, to which is attached 70 the two-pallet valve 66. This valve, according to its position, admits either wind-pressure from the chamber 63 or atmospheric pressure from the chamber 64 to the supply-passage 67, leading to the interior of the bellows-motor 68, thus distending the bellows or permitting it to collapse, as the case may be. The bellows-motor 68 is one of a series placed close to and corresponding in number with the set of pedal-tablets 102 105. The supply-passage 67 of these motors are all connected by the passage 71, so that all the motors of the series operate simultaneously with the closing of the circuit by the collar 28 and the collapsing of the primary bellows 62. 80

Below the series of motors 68 is a similar series of larger motors 93, 94, 95, and 96, and these two series are so located that the forward end of each tablet, as 105, is engaged by the outer ends of one each of the upper and lower motors, as shown in Fig. 2. The motors 93, 94, 95, and 96 are each controlled, similarly to the motor 68, by a magnet 76 and a primary bellows 87. The supply-passages 86 are, however, not connected, as in 90 the case of the upper series; but each motor is provided with its own magnet 73 74 75 76 and primary 87, thus enabling each motor of the lower-series to act independently of all the others. 95

When both motors, as 68 and 93, are collapsed, the inner end of the corresponding tablet is free and may be operated by hand by touching its outer end. If, however, wind-pressure is admitted to the series of 105 motors 68, such of the tablets 102 104 as are in the on-position will be immediately thrown off and the whole series of pedal-tablets will be kept in the off position until the resistance of the upper motors is overcome. When 110 wind is admitted to one of the lower motors, as 93, its connected tablet 105 will be immediately thrown to the on position, as the greater area of the lower motor enables it to move the tablet in spite of the resistance of 115 the corresponding upper motor. This is the position of the parts in Fig. 2, where it will be noticed both the motors 68 and 93 are in communication with their respective pressure-chambers 63 and 88. The tablet 105 is 120 supposed in this instance to represent the great-to-pedal coupler, and is therefore thrown on as soon as the lower or great suitable bass rod is pushed in. It will be noted also from the foregoing that the motors 68 125 obstruct the pedal-tablets from being thrown on by hand when either of the suitable bass rods is in its on position, as the unusual resistance of the tablet will at once indicate to the organist that the suitable bass parts 130

are in their operative position. Even should he by accident or inadvertence push hard enough to overcome the pressure of the motor 68 the tablet would remain in the operative position only so long as the outer end is held down from the outside.

The wire 40 of the circuit of the collar 30 leads, by means of branch wires 135, 136, and 137, Fig. 4, to contact-points in the vicinity 10 of each of the great-organ tablets 126, &c. A contact-plate 132 133 134 is provided on the inner end of each tablet 126 127 128, Figs. 3 and 4, and closes the circuit across the contact-points of the wires 135 and 138, 136 and 139, 137 and 140 when the tablet is moved 15 to its on position. Each wire 138 139 140, &c., leads to the electropneumatic valve which controls that motor of the series 96 95 94, &c., which will throw on the tablet 102 103 104, &c., of a pedal-stop suitable to 20 accompany the manual-stop of the tablet 126 127 128, &c., to which the wire 138 139 140, &c., is connected. More than one pedal-stop may be connected with any one of the 25 manual-stops by providing additional contact-points for the tablet 127 and connecting them as above described.

The wires 41 and 42 of the collar 31 are provided for the purpose of forming a circuit 30 which will enable the tablets 123, &c., of the swell-organ to operate their respective suitable bass stops whenever the great and the swell organs are coupled together. The tablet 128, Fig. 4, represents the great-to-swell 35 coupler and is seen to be provided with three contact-points, so that the current passing through the wire 137 passes to the wire 41 as well as to the wire 140. The latter operates the swell-to-pedal motor 94, as described 40 above in connection with the motor 93. The wire 41 is connected, by means of the collar 31, to the wire 42, leading to the contact-points of the swell-organ tablets 123, &c. When one of these tablets is thrown on, it will therefore 45 fore throw on at the same time its own suitable bass stop. The wire 41 could be joined directly to the wire 42 without the intervention of the collar 31 and still perform its function properly so far as the great organ is concerned; but when the swell-organ suitable 50 bass rod is pushed in the direct joining of these two wires would permit the current to pass through the contact-plate 134, Fig. 4, if the tablet 128 happened to be on at the 55 moment, to the contact-plates 132, &c., of any of the great-organ tablets which also happened to be on, thus causing their connected suitable bass stops to be thrown on, and these stops would be unsuitable for the stops 60 of the swell-organ. The circuit is therefore carried through the collar 31, so that the circuit will be opened when the suitable bass rod 25 of the great organ is pushed off by the pushing on of the swell-rod 15.

65 The mode of operation of these devices is

as follows: When the suitable bass rod 25 of the great organ is pushed in, the collars 28, 29, and 30 join the wires 38, 39, and 40 to the battery through the contacts 32 33 34 36 and the battery-wire 48, the wires 41 and 42 being 70 at the same time joined by the collar 31. The current immediately passes over the wires 38 and 39. The former energizes the magnet 51, Fig. 2, causing it to lift the valve-disk 52 from its seat in the recess 54, thereby operating, as above described, to expand all the motors 68 which are connected by the pipe or tube 71, and thus throwing off such of the tablets 102, &c., as are in the on position. This upper series of motors therefore tends 80 to hold all the pedal stops and couplers in their off positions as long as the suitable bass rod 25 remains pushed in. The current also passes immediately over the wire 39 as soon as the rod 25 is pushed in. The magnet 76 85 is therefore energized and causes one of the larger motors 93 of the lower series to expand, thereby throwing on the "great-to-pedal" coupler by means of the tablet 105 overcoming the resistance of the upper 90 motor 68. This is the position of the parts shown in Fig. 2, both motors 68 and 93 being in communication with the chambers 63 and 88, and therefore containing air under pressure. The pushing in of the stop-rod 25 95 may not immediately cause the current to pass over the wire 40, as the circuit may be open at other points. Let us now suppose that the tablets 126 and 127 of the great organ (represented in Fig. 4) are those of the 100 open diapason and the Hohl-flute stops, that the tablet 128 is that of the swell-to-great coupler, as already explained, while the four tablets 102, 103, 104, and 105 of the pedal-organ are those of the open diapason-stop, 105 the Bourdon stop, the swell-to-pedal coupler, and the great-to-pedal coupler, respectively. If now the second one of the great-organ tablets 127—the Hohl flute—be thrown on, the current will pass from the wire 40 through the branch 136 and the contact-piece 133 to the wire 139. The magnet 74, controlling the large motor 95, will be energized and cause that motor to expand and throw on the pedal Bourdon stop by means of its tablet 103, this action also taking place against the resistance of the corresponding smaller motors 68, this being the position of the parts shown in Figs. 1, 2, 3, and 4. Similarly, if the open diapason-tablet 126 be thrown on 110 the current will pass and operate the motor 96 and throw on the open diapason pedal-stop. It will also be seen that two or more pedal-stops may be thrown on by the operation of one of the manual-stops by supplying 115 the latter with additional contact-points. If now the great-organ tablet 128, the swell-to-great coupler, be operated, the current will pass from the branch 137 to the wires 140 and 41. The former wire will throw on 120 the tablet 105, this action also taking place against the resistance of the smaller motors 68, this being the position of the parts shown in Figs. 1, 2, 3, and 4. Similarly, if the swell-to-pedal tablet 127 be thrown on 125 the current will pass and operate the motor 96 and throw on the swell-to-pedal pedal-stop. It will also be seen that two or more pedal-stops may be thrown on by the operation of one of the manual-stops by supplying 130 the latter with additional contact-points.

the pedal-tablet 104, and thereby operate the swell-to-pedal coupler. The latter wire establishes a circuit through the insulated collar 31 to the wire 42, which leads by 5 branches 120, 121, and 122 to each of the contact-plates of the stop and coupler tablets 123, 124, and 125 of the swell-organ, thus permitting each one of them to operate its suitable bass stop by means of one of the 10 wires 147, similarly as described for the great organ. When any one of the tablets 126, &c., is thrown again to its off position, the pressure in its connected large motor is exhausted, thus permitting the corresponding 15 small motor, which is always supplied with pressure while the rod 25 is pushed in, to act and throw off its pedal-stop. When the suitable bass rod 15 of the swell-organ is pushed in, the current passes over the wire 141 to the wire 38 and throws off all the 20 pedal-stops as before, while the current over the wire 142 passes to the wire 140 and throws on the swell-to-pedal coupler. The current may also now pass over the wire 143 25 to the wire 42 and its branches as soon as any of the swell-tablets are thrown on, thus bringing on suitable pedal-stops through the wires 147, as already described. A collar corresponding to the collar 31 is unnecessary 30 on the suitable bass rod 15 of the swell-organ, as the great organ is never played from the swell-organ. By means of the mechanism referred to in connection with the latch-board 21 only one of the suitable bass rods 35 15 or 25 can be in its pushed-in position at the same moment. The circuit over the wires 41 and 42 through the collar 31 is therefore broken as soon as the swell-rod 15 is pushed in, thus preventing the current from 40 passing through the contact-piece 134 of the swell-to-great coupler-tablet 128 in case it happens to be on, and thereby preventing the drawing on of the suitable pedal-stops of such of the great-organ stops as also happen 45 to be on at the moment.

In Fig. 5 is shown in diagrammatic form one method of controlling and operating the automatic suitable bass mechanism by pneumatic means. The suitable bass knobs 14 and 24 and rods 15 and 25 are arranged, as before, within convenient reach of the organist and are provided with a similar mechanism, permitting only one of the rods to be in the pushed-in position at the same time. 50 When one of the rods—as, for example, that of the great organ—is pushed in, the wedge, 153 lifts the valve 152, admitting pressure from the chamber 151 to the tubes 154 and 156. From the latter it passes through the 55 check-valve box 162 to the tube 166, being prevented from entering the tube 188 to the swell-pressure chamber 189 by the check-valve 161, which may be of any well-known form. The pressure through the tube 166 60 equalizes the pressure on both sides of the

primary bellows 167, thus enabling the spring 171 on the end of the lever 170 to draw up the valve 168 and admit pressure through the passage 169 and 71 to the series of small motors 68, which act, as before, to throw off all the pedal-tablets 102, &c. The pressure through the tube 155 equalizes the pressure in the primary bellows 192 and operates the motor 93, connected with the great-to-pedal coupler. From the tube 154 75 the pressure also passes through the tube 157 and its branches to the duct-boxes 174, 175, and 176. These are provided with valves 177 of any approved form, which are operated by the tablets 127, &c., of the great organ. When one of these tablets, as 127, is thrown on, the pressure passes through the corresponding tube 181 and operates an associated motor similar to 93 by means of a primary bellows similar to 192. In the same 80 way if the tablet 128 of the great-to-swell coupler is thrown to the on position as shown, the pressure will not only pass to the associated tube 181, but will also pass, by means of the tube 184, to the duct-boxes 197, &c., of the swell-organ. Valves 180, &c., when operated by the respective tablets of the swell-organ admit the pressure to the tubes 182, by which the suitable stops in the pedal department are operated. The operation of the 85 pneumatic devices in connection with the swell suitable bass rod 15 is similar to that of the great. When pressure is admitted from the chamber 189 to the tube 186, it passes through the tube 188 and the tube 166 to the off primary bellows 167, the check-valve 161 swinging over and closing the entrance to the tube 156. The pressure passes also to the tube 191, which operates the swell-to-pedal-coupler motor, and to the tube 190, 90 from which it reaches the duct-boxes 179, the valve 187 swinging over and preventing any pressure from passing through the tube 184 to the stop-actions, which should be operated only from the great organ. 95

In Figs. 6 and 7 is illustrated a method of arranging the composition-pedals of the organ so that a suitable bass may be easily and conveniently provided for each composition of stops. The composition-pedal 226 100 is of a well-known type, being pivoted at 227 and having a spring 228 to return it to its off position when released. Each of these 105 pedals is connected to its particular combination of manual stops and couplers by any well-known means, either electric, pneumatic, or electropneumatic. In Fig. 6 electric means are shown, in which 260 is a contact-piece appurtenant to the pedal 226, 261 a wire leading to the battery, while a number 110 of contact-points 262 and wires 263 lead to the different stops of the great (or swell) organ controlled by this particular pedal. 115 Adjacent to the pedal 236 and pivoted at 237 is a subsidiary composition-pedal 236, 120

connected by any well-known means with some stop or combination of stops and couplers in the pedal-organ which will form a suitable bass for the combination of stops controlled by its associated upper pedal 226. The means by which this pedal controls its connecting-steps are here also shown to be electric. The contact-piece 270 is appurtenant to the subsidiary pedal 236 and has a wire 271 leading therefrom to the battery, while a number of contact-points 272 and wires 273 lead to the different stops controlled by this particular pedal. The foot-piece 239 of the subsidiary pedal 236 is placed just below and in front of the foot-piece 229 of the upper pedal. A spring 238, preferably stiffer than the spring 228 of the upper pedal, returns the subsidiary pedal to its off position when released. Both pedals extend through an opening 248 in the console-frame 11, the top 249 of the opening serving as a stop for the upward movement of the upper pedal 236, while the bottom 250 of the opening serves as a stop for the downward movement of the lower pedal 236. The upward movement of the latter is stopped by the rod 246. The two pedals 226 and 236, with their stops, are so located relatively to each other that the foot of the organist will come in contact with the foot-piece 239 of the lower pedal after the upper pedal has been moved a predetermined distance. This amount of movement is more than enough to cause the first pedal to throw on its connected stops and couplers, and the increased resistance due to the compressing of both springs at the same time enables the organist to know just when the second pedal is put in operation. The lower pedal may also be operated independently of the upper one, and the difference in the stiffness of the springs indicates to the organist which of the two pedals he has his foot on. The operation of the parts is as follows: In bringing one of the composition-pedals 226 into play the organist puts his foot upon it in the usual manner. After the pedal has descended a short distance and has thrown on its own combination of stops and couplers the foot of the organist will come in contact with the subsidiary composition-pedal 236, and if he exerts an increased amount of pressure the subsidiary composition-pedal will also be operated and bring on the necessary pedal stops and couplers to form a suitable bass to the combination drawn on by the associated upper composition-pedal 226.

It is obvious that the method of arranging the subsidiary composition-pedal in connection with the ordinary composition-pedal may be varied considerably. The upper pedal may be arranged to contact upon the lower pedal, so as to push it downward without its foot-piece being engaged by the foot of the organist, or the pedals may be placed side by side, their pivots substantially in line, and the foot-pieces may be arranged to stand side by side during their common movement. It is obvious also that pairs of tablets to be operated by the hand of the organist could be arranged to produce similar results.

An important feature of the suitable bass apparatus, as described above in connection with the suitable bass rods 15 and 25, is that it always operates the pedal stop and coupler tablets, as well as the stops and couplers themselves, thus indicating to the eye what stops or combinations of stops have been affected. The position of the organ-stops is therefore always indicated to the organist in the same way, whether the suitable bass is in operation or not.

The terms "upper," "lower," "inner," "outer," and similar terms denoting relative position are herein used in their relative and not their absolute sense, inasmuch as the parts herein shown may be reversed, inverted, or transposed in many ways that will be obvious to the organ builder or designer. The actions, circuits, and connections herein shown and described may be modified in many obvious ways to suit different sizes of organs or to suit various conditions of space and service.

I claim as my invention—

1. In an organ, a series of stops, a series of tablets, and connections therefrom for controlling the stops, a series of motors connected with the tablets for moving them to their off positions, and a controlling-motor for the said series of motors. 95
2. In an organ, a series of stops, a series of tablets and connections therefrom for controlling the stops, a series of motors connected with the tablets for moving them to their off positions, a controlling-motor for the series of motors, and a manually-operated device for inaugurating the operation of the controlling-motor. 105
3. In an organ, a series of stops and couplers, a series of tablets and connections therefrom for controlling the stops and couplers of one department of the organ, a series of motors for throwing all the stops and couplers and their corresponding tablets to their off position, and a single device for simultaneously energizing all the motors of the series and for causing the operation of one or more of the couplers. 115
4. In an organ, the combination of a series of stops and couplers, a series of tablets for controlling the stops and couplers, a series of off motors, a more powerful series of on motors for operating the tablets, and means for coincidentally energizing the series of off motors and one or more of the on motors, whereby the latter overcome the force of their respective off motors and operate their respective tablets. 125
5. In an organ, the combination with the 130

- stop and coupler devices of a series of off motors and an opposing series of more powerful on motors, selecting devices for independently energizing each on motor, and 5 means for simultaneously energizing the off motors and for putting the stop and coupler devices into operative relation with the selecting devices.
6. An organ having a plurality of departments, stop-controllers for one department, stop-controllers for a second department, devices for automatically operating the stop-controllers of one department from the stop-controllers of another department, and devices for visibly indicating the on and off 10 positions of each stop-controller thus operated.
7. An organ having a plurality of departments, stop and coupler controllers for one 15 department, stop and coupler controllers for another department, and devices for automatically operating the stop and coupler controllers of one department from the stop and coupler controllers of another department, and devices for visibly indicating the on and off 20 positions of each stop and coupler controller operated.
8. In an organ, the combination with two manuals and their stops and couplers, of bass 25 stops, connections for bringing on suitable bass stops for whatever stops may be drawn on either of the manuals, and means for rendering the said connections active for one of the manuals and inactive for the other manual.
9. In an organ, a series of stop and coupler controllers, means for simultaneously throwing a group of stop and coupler controllers to their off positions, and means for throwing individual stop or coupler controllers of the group independently to their on 35 positions by overcoming the action of the off means.
10. In an organ, a series of stop and coupler controllers, a series of simultaneously-operating motors for throwing said series of stop and coupler controllers to their off positions, a series of independently-operating larger motors for overcoming the action of the off motors and throwing the said stop and coupler controllers to their on positions, and means operable by the performer for simultaneously energizing all the off motors and rendering the on motors operable. 45
11. An organ having a plurality of departments, a series of stop and coupler controllers for each department, a series of simultaneously-operating motors for throwing the stop and coupler controllers of one department of the organ to their off positions, a series of independently-operating larger motors for overcoming the action of the off motors and throwing the said stop and coupler controllers to their on positions, and means operated by a single device, as a push-button, 55 for simultaneously energizing all the off mo-
- tors and for rendering each on motor operable by a controller in another department of the organ.
12. An organ having a plurality of departments, a series of stop and coupler controllers for each department, a series of pneumatic motors for throwing the stop and coupler controllers of one department of the organ to their off positions, a second series of independently-operable larger pneumatic 70 motors for overcoming the action of the off motors and throwing the stop or coupler controllers to their on positions and means operable by a single device, as a push-button, for simultaneously energizing all of the off 75 motors and rendering each on motor independently operable.
13. An organ having a plurality of departments each with a plurality of stops, a series of stop-controllers for one department of the 80 organ, a series of stop-controllers for a second department of the organ, and a series of connections connecting the two sets of stop-controllers whereby a controller of one department is connected with the controller of 85 a suitable stop of the second department.
14. An organ having a plurality of departments, a series of stop-controllers for one department of the organ, a series of stop-controllers for a second department of the organ, 90 connections including a series of electric circuits connecting the two sets of controllers whereby a controller of the first department is connected with the controller of a suitable stop of the second department, and a single 95 device for simultaneously rendering all of the said circuits operable.
15. An organ having a plurality of departments, a series of stop-controllers for one department of the organ, a series of stop-controllers for a second department of the organ, 100 connections including a series of electric circuits connecting the two sets of controllers, whereby a controller of the first department is connected with the controller of a suitable 105 stop or stops of the second department, a device for coupling the first department to the second, and a single device for simultaneously rendering all of the circuits operable and causing the coupler to act. 110
16. An organ having a plurality of departments, a series of stop-controllers for one department of the organ, a series of stop and coupler controllers for a second department of the organ, connections including a series of 115 electric circuits connecting the two sets of controllers whereby a stop-controller of the first department is connected with the controller of a suitable stop or stops of the second department a series of tablets for manually operating the controllers of the second department, and a single device for simultaneously rendering all of the said electric 120 circuits operable, for causing the coupler for coupling the first department to the second 125 130

- to act, and for rendering the said series of tablets inoperable.
17. An organ having a plurality of departments, a series of stop-controllers for one department of the organ, a series of stop-controllers for a second department of the organ, a series of motors for causing the stop-controllers of the second department to bring on their respective stops, means connecting the series of motors to the controllers of the first department, a controller of said first department being connected through said means and motors with a suitable controller or controllers in the second department.
18. An organ having a plurality of departments, a series of stop-controllers for one department of the organ, a series of stop-controllers for a second department of the organ, a series of motors for causing the controllers of the second department to bring on their respective stops, means connecting the series of motors to the controllers of the first department, a controller of said first department being connected through said means and motors with a suitable controller or controllers in the second department, and a single device for rendering the said means operable.
19. An organ having a plurality of departments, a series of stop-controllers for one department of the organ, a series of stop-controllers for a second department of the organ, a series of motors for causing the controllers of the second department to bring on their respective stops, means connecting the series of motors to the controllers of the first department, each of said first-department controllers being connected through said means and motors with a suitable controller or controllers in the second department, a coupler-controller for causing the coupling of the second department to the first, and a single device for rendering the said means operable, and for rendering the coupler-controller to act.
20. An organ having a plurality of departments, a series of stop-controllers for one department of the organ, a series of stop-controllers for a second department of the organ, a series of motors for causing the controllers of the second department to bring on their respective stops, means connecting the series of motors to the controllers of the first department, each of said first-department controllers being connected through said means and motors with the controller of a suitable stop in the second department.
21. An organ having a plurality of departments, a series of stop-controllers for one department of the organ, a series of stop-controllers for a second department of the organ, a series of motors for causing the controllers of the second department to bring on their respective stops, means connecting the series of motors to the controllers of the first department.
22. An organ having a plurality of departments, a series of stop-controllers for one department of the organ, a series of stop-controllers for a second department of the organ, a series of motors for causing the controllers of the second department to bring on their respective stops, means connecting the series of motors to the controllers of the first department, each of said first-department controllers being connected through said means and motors with the controller of a suitable stop in the second department, a coupler-controller for causing the coupling of the first department to the second, and a single device for rendering the said motors operable, and for causing the coupler-controller to act.
23. An organ having a plurality of departments, a series of stop-controllers for one department of the organ, a series of stop-controllers for a second department of the organ, means for manually operating said stop-controllers, a series of motors for causing the controllers of the second department to bring on their respective stops, means connecting the series of motors to the controllers of the first department, each of said first-department controllers being connected through said means and motors with the controller of a suitable stop in the second department, a coupler-controller for causing the coupling of the first department to the second, and a single device for rendering the said motors operable for causing the coupler-controller to act, and for rendering inoperative the manually-operating means for the stop-controllers of the second department.
24. An organ having a plurality of departments, a series of stop-controllers for one department of the organ, a series of stop-controllers for a second department of the organ, a series of bellows for causing the controllers of the second department to bring on their respective stops, a series of electropneumatic motors controlling the series of bellows, a series of electric circuits connecting the electropneumatic motors with the controllers of the first department, a controller of said first department being connected through the electropneumatic motors with a suitable controller or controllers in the second department.
25. An organ having a plurality of departments, a series of stop-controllers for one department of the organ, a series of stop-controllers for a second department of the organ, a series of bellows for causing the controllers of the second department to bring on their respective stops, a series of electropneumatic motors controlling the series of bellows.

lows, a series of electric circuits for connecting the electropneumatic motors with the controllers of the first department, a controller of said first department being connected through the electropneumatic motors with a suitable controller or controllers in the second department, and a single device for simultaneously closing all of the circuits so as to render each one of them operable whenever its connected first-department controller is operated.

26. An organ having a plurality of departments, a series of stop-controllers for one department of the organ, a series of stop-controllers for a second department of the organ, a series of bellows for causing the controllers of the second department to bring on their respective stops, a series of electropneumatic motors controlling the series of bellows, a series of electric circuits connecting the electropneumatic motors and the controllers of the first department, a controller of said first department being connected through the electropneumatic motors with a suitable controller or controllers in the second department, means for controlling the coupling of the first department to the second, a bellows for operating the coupler-controller, an electropneumatic motor for causing the bellows to operate a circuit therefor, and a single device for simultaneously closing all of the said electric circuits, so as to render each one of them operable whenever its connected first-department controller is operated, said single device serving also to close the circuit of the electropneumatic motor of the coupley-bellows.

27. An organ having a plurality of departments, a series of stop-controllers for one department of the organ, a series of stop-controllers and coupler-controllers for a second department of the organ, a series of bellows for moving the controller to bring on their respective stops and couplers, a series of electropneumatic motors controlling the said series of bellows, a series of electric circuits connecting some of the electropneumatic motors with the controllers of the first department, a series of electric circuits to operate the coupler electropneumatic motors, a series of smaller bellows connected with the said second series of controllers for throwing them to their off positions, an electropneumatic motor controlling the series of smaller bellows and provided with an electric circuit, and a single device for simultaneously closing all the said electric circuits, so as to immediately energize the smaller bellows and coupler-circuits, and to close the circuits connecting the first and second departments.

28. An organ having two departments each with a plurality of stops, a controlling device for bringing on a series of stops in one department of the organ, a controlling device for bringing on a series of stops forming a

suitable accompaniment thereto in the second department of the organ, and means whereby a predetermined amount of movement of the first controlling device will also operate the second controlling device.

29. An organ having two departments each with a plurality of stops, a controlling device for bringing on a series of stops in one department of the organ, a controlling device for bringing on a series of stops forming a suitable accompaniment thereto in the second department of the organ, and means connecting the two controlling devices whereby the first controlling device after a predetermined amount of movement, will operate the second controlling device.

30. An organ having two departments each with a plurality of stops, a controlling device for bringing on a series of stops in one department of the organ, an independently-operable controlling device for bringing on a series of stops forming a suitable accompaniment thereto in the second department of the organ, and means whereby the first controlling device after a predetermined amount of movement will also operate the second controlling device.

31. An organ having two departments each with a plurality of stops, a device for bringing on a series of stops in one department of the organ, a device for bringing on a series of stops forming a suitable accompaniment thereto in another department of the organ, and means whereby both devices may be operated by one movement, the devices being provided with springs of different tension to indicate to the touch whether one, the other, or both devices are being operated.

32. An organ having two departments each with a plurality of stops, a series of actions controlling the stops of one department of the organ, a series of actions controlling the stops of a second department of the organ and a series of electric circuits and devices controlled thereby connecting the two series of actions whereby the operation of the stops of the first department is made dependent upon the position of the actions of the second department.

33. An organ having a plurality of departments each with a plurality of stops, a controller for a stop in one department, and devices under the control of the performer for connecting and disconnecting a stop in a second department with said controller whereby the controller controls either a stop in the first department only or controls the stop in that department and a stop in the second department at the will of the operator.

34. An organ having a plurality of departments each with a plurality of stops, a controller for each stop in one department, and devices under the control of the performer for connecting and disconnecting a stop in a second department with each stop-controller

of the first department whereby each controller controls either a stop in the first department or a stop in that department and a stop in the second department at the will of the operator.

35. An organ having a plurality of departments each with a plurality of stops, a controller for a stop in one department, devices under the control of the performer for connecting a stop in a second department with said controller and devices for simultaneously coupling the first department to the second.

36. An organ having a plurality of departments each with a plurality of stops, a controller for each stop in one department, devices for connecting a stop in a second department with each controller of the first department, devices for coupling the first department to the second, and means under the control of the performer for rendering the connecting devices active and causing the coupling device to act.

37. An organ having a plurality of departments each with a plurality of stops, manually-operated controllers for the stops in each department, devices under the control of the performer for connecting and disconnecting the controllers of one department with the corresponding controllers in a second department whereby the controllers control either stops in the first department only or control said stops in the first department and stops in the second department at the will of the operator.

38. An organ having a plurality of departments each with a plurality of stops, manually-operated controllers for the stops in each department, devices for coupling one department to another, and devices under the control of the performer for connecting the controllers in one department with controllers in another department and simultaneously causing the coupling devices to act.

39. An organ having a plurality of departments each with a plurality of stops, a controller for a stop in one department, devices under the control of the performer for connecting a stop in a second department with said controller, a controller for a stop in a third department, devices for coupling the third department to the first, and devices controlled by said coupling devices for connecting a stop of the second department with the controller of the third department.

40. An organ having a plurality of departments each with a plurality of stops, a con-

troller for each stop in one department, devices under the control of the performer for connecting a stop in a second department 60 with each controller of the first department, a controller for each stop in a third department, devices for coupling the third department to the first, and devices controlled by said coupling devices for connecting a stop in 65 the second department with each controller of the third department.

41. An organ having a plurality of departments each with a series of stops, a series of stop-controllers for one department, a second 70 series of stop-controllers for a second department, and means under the control of the operator for operating one series of stop-controllers from the other.

42. An organ having a plurality of departments each with a series of stops, a series of stop-controllers for one department, a second series of stop-controllers for a second department, connecting devices between the two series of stop-controllers under the control of 80 the operator for operating the stops of one department through the operation of the stop-controllers of the other department.

43. An organ having a plurality of departments each with a plurality of stops, a series 85 of actions for controlling the stops of one department, a series of actions for controlling the stops of a second department, and connecting devices between the two series of actions under the control of the operator where- 90 by the operation of the stops of one department may be made dependent upon the position of the actions of the other department.

44. An organ having a plurality of departments each with a plurality of stops, devices 95 under the control of the performer for connecting and disconnecting a stop in one department with a stop in another department so that the stops may be operated in unison or one independently of the other.

45. An organ having a plurality of departments each with a plurality of stops, devices under the control of the performer for connecting and disconnecting at will each stop of one department with a stop in a second department.

In testimony whereof I have signed my name to this specification in the presence of two subscribing witnesses.

ROBT. HOPE-JONES.
